UNITED STATES PATENT OFFICE.

WILLIAM DUFFIELD, OF LONDON, ONTARIO, CANADA.

DESIGN FOR AN ARGAND-LAMP CHIMNEY.

SPECIFICATION forming part of Design No. 16,398, dated December 1, 1885.

Application filed October 17, 1885. Serial No. 180,212. Term of patent 3½ years.

To all whom it may concern:

Be it known that I, WILLIAM DUFFIELD, a subject of the Queen of Great Britain, residing at London, in the county of Middlesex and the Province of Ontario, Dominion of Canada, have invented and produced a new and original Design for an Argand-Lamp Chimney, of which the following is a specification, reference being had to the accompanying drawing, forming part thereof.

This chimney is shaped with a throat or neck, C, having a bulbous enlargement, B, on one extremity, the walls A of which gradually approach to the top of the chimney, the other extremity of the neck C having an annular offset terminating in a cylindrical extension or base, D.

I am aware that an Argand-lamp chimney

has been constructed in which the bulbous enlargement, similar to that marked B, is shown; but in that chimney the bulb is connected immediately to the base D without the intermediate throat or neck, C.

The lines marked *a* and *b* in my design show the points at which the flame is cut. 25

I claim—

The design for an Argand-lamp chimney herein shown and described, the same consisting of the throat or neck C, the bulb B at one extremity of this throat, and the annular offset terminating in the cylindrical extension or base D. 30

WILLIAM DUFFIELD. [L. S.]
